CLAIM

The ornamental design for a hand-held washing machine as shown and described.

DESCRIPTION

FIG. 1 is a front elevational view of a hand-held washing machine showing our new design;

FIG. 2 is a rear elevational view thereof;

FIG. 3 is a right side view thereof;

FIG. 4 is a left side view thereof;

FIG. 5 is a top view thereof;

FIG. 6 is a bottom view thereof;

FIG. 7 is a perspective view thereof; and,

FIG. 8 is another perspective view thereof.

The dash-dash broken lines with de-emphasized shading in FIGS. 1 and 7 depict elements that form no part of the claimed design.

1 Claim, 8 Drawing Sheets
